UNITED STATES PATENT OFFICE.

ADAM W. KAUFMAN, OF MILWAUKEE, WISCONSIN.

TIMER.

Application filed March 7, 1922. Serial No. 541,678.

To all whom it may concern:

Be it known that I, ADAM W. KAUFMAN, a citizen of the United States, and resident of Milwaukee, in the county of Milwaukee and State of Wisconsin, have invented certain new and useful Improvements in Timers; and I do hereby declare that the following is a full, clear, and exact description thereof.

10 My invention relates to a new and improved timer for use in connection with internal combustion engines.

The general object of the invention is to provide means, whereby a smooth and uniform contact may be effected with the least possible wear and friction upon the contacting elements.

A more specific object of the invention is to provide means whereby one or both 20 of the contacting elements has a yieldable and floating connection with its support, so that a full contact may be made between the same with the least possible amount of friction.

25 A further object of the invention is to provide means whereby the contacting elements may be conveniently renewed at comparatively slight expense whenever the surface thereof becomes worn or irregular.

30 With the above and other objects in view, the invention consists in certain details of construction and combinations thereof, which will be more particularly described in connection with the accompanying drawing and subsequently claimed.

In the drawing,

Figure 1 represents a plan view of my invention with a portion broken away in order to show the interior construction.

40 Figure 2 represents a vertical sectional view thereof.

Figures 3 and 4 represent detail views taken on the lines 3-3 and 4-4 respectively of Figure 1.

45 Referring more specifically to the drawings, the numeral 5 designates the outer shell of the timer, and 6 designates a rotary shaft mounted centrally thereof. The shell 5 is provided with a plurality of binding 50 posts 7, which are suitably insulated, one binding post being provided for each cylinder of the engine. The binding posts are disposed radially and each is provided at its inner end with a retaining head 8, which secures a metallic yoke 9, which may be conveniently formed by stamping. This

yoke is formed with inwardly extending end portions 10 which are offset towards each other, as shown at 11, and provided with transversely disposed heads 12. An inwardly bowed shoe 13 is slidably mounted upon the arms of the yoke and is provided with lugs 14 at each end of which engage the sides of the arms 11 and the heads 12, and the shoe is normally held in this position by means of a coil spring 15. The shoe may be easily removed from the yoke or replaced by depressing the same in opposition to the spring 15, so that the lugs 14 may be slipped laterally underneath the 70 offset portions 11 of the yoke arms.

The rotor 16, which is preferably made by die casting, is secured to the shaft 6, and is provided with outwardly extending parallel arms 17, the opposed faces of which 75 are provided with L shaped slots 18, the inner laterally extending portions 19 of the slots being for the purpose of inserting a removable contact element 20. This contact element has its intermediate portion 80 outwardly bowed so as to make a uniform wiping contact with the shoe 13, and is provided with inwardly extending legs 21, which terminate in the feet 22, which are slidably engaged in the slots 18. A coil 85 spring 23 yieldingly supports the contact element 20 normally in its outermost position.

In the operation of my invention, the contact element or brush 20 is carried successively into contact with the several shoes 13, first engaging the same near one end with a smooth wiping contact, while the springs 15 and 23 permit the adjacent ends of the contact elements to yield slightly. 90 As the rotor advances, the floating nature of the contacting elements allows the same to gradually change their positions with relation to each other, so as form at all times, a smooth and uniform contact. Although a full contact is made, the friction is, by means of this structure, reduced to a minimum. In case, however, the contacting elements become worn or their surface irregular, the same may be replaced at a 100 trifling cost.

While I have shown and described both contacting elements as having a floating support, it will be seen that very good results may be obtained if only one of them 110 has a floating support.

It will also be appreciated that various

modifications may be made in the structural details of the invention, within the scope of the appended claims.

I claim as my invention:

- 5 1. A timer comprising a plurality of radially disposed binding posts, each having a yoke secured to its inner end, an inwardly bowed contact member slidably mounted in said yoke, and yieldably held in its innermost position, and a rotor having a brush adapted to wipe the contact members successively.
- 10 2. A timer comprising a plurality of binding posts, disposed radially and each

having a yoke secured to its inner end, said yoke having inwardly extending arms formed with stops at their inner ends, a contact member removably and slidably mounted on the arms of the yoke, a spring normally holding the contact member against the stops, and a rotor having a yieldable brush adapted to wipe the contact members successively.

In testimony that I claim the foregoing I have hereunto set my hand at Milwaukee, 25 in the county of Milwaukee and State of Wisconsin.

ADAM W. KAUFMAN.
